ABSTRACT OF THE DISCLOSURE

Smoke detection apparatus including a visual smoke detector comprising a dark chamber providing an air path, a light-carrying rod, such as a glass fibre light guide, for conveying light from a light source and for causing this to pass along a light path through the air path, and a window through which the light path may be viewed.

In an arrangement such as that described in the abstract when even a small amount of smoke is entrained in the air passing through the air path a viewer looking through the window will see light reflected by smoke particles passing through the light path.

A second light-carrying rod may be provided spaced by a small gap from the end of the first-mentioned rod, the said gap constituting the light path. This second rod preferably carries the light received from the first rod to provide a source of illumination for a second smoke detector. This second smoke detector preferably incorporates a light sensitive electric cell.

The second smoke detector may conveniently comprise two light paths lying between and extending respectively from the said light source and the said electric cell and being mutually inclined so that the said electric cell is masked from the light source, the arrangement being such that when smoke particles are present at the intersection between the two light paths, these smoke particles cause light from the light source to be deflected on to the light sensitive electric cell. Preferably, the said light paths are inclined to each other by an obtuse angle, preferably 120° or greater and in a preferred embodiment 150°. Preferably, the light paths are formed in a block so arranged that the intersection of the light paths take place at a location spaced from the block, the block preferably having a flat surface located between the light paths. The smoke detection apparatus preferably comprises a single housing for both detectors.

Preferably the apparatus comprises a plurality of units, there being a single source of light to which the remote ends of the said first rods are exposed.

An embodiment of the invention will now be described, by way of example, with reference to the accompanying drawings.

In the drawings:

FIGURE 1 is a perspective view of a system comprising two banks of units of the invention,

FIGURE 2 is a side view of the system of FIGURE 1 with side walls of the apparatus housing removed,

FIGURE 3 shows the light source for one bank,

FIGURE 4 is the front view of smoke detection unit of the invention,

FIGURE 5 is a section on line 5—5 of FIGURE 4,

FIGURE 6 is a section on line 6—6 of FIGURE 5, and

FIGURE 7 is a circuit diagram showing the main circuit and the circuit for one unit.

Referring now to FIGURES 1, 2 and 3, there is shown two banks of upwardly inclined smoke detection units 10 for use in a ship and two light sources 11. Each light

source 11 comprises a quartz iodine axial filament lamp 12. The lamp 12 is located in a light-proof housing 13 (see FIGURE 3) having a hinged door 14 (see FIGURE 2) for removal of the lamp 12. A plurality of rods 15, one for each unit 10 in a bank, have their ends (hereinafter called their "remote ends") opening into the housing 13. These rods 15 may be made of glass or "Perspex" (registered trademark) or may preferably be fibre optical rods. The other (or inner end) of each rod 15 is connected to a union 16 secured into the upper wall of the housing of a smoke detection unit 11.

The housing 17 of each detector unit comprises front, rear, top and bottom walls 17a, 17b, 17c and 17d respectively. Two intermediate walls 17e and 17f are also provided parallel to the top and bottom walls. The front wall 17a is the widest wall, the intermediate walls 17e and 17f being slightly less wide but wider than the remaining walls. The intermediate walls 17e and 17f slot into recesses in the side walls of the cabinet 18 to form an air and light-tight seal therewith.

The rear wall 17b of the housing 17 has an air inlet socket 19 and above it an air outlet socket 21. The inlet socket 19 is connected by means of a flexible pipe 22 (not shown) to a hold of the ship. The outlet socket 21 is connected by a conduit 22 to a header chamber 23 common to each bank. A suction pump 20 applies suction pressure to each header chamber 23. The outlet from the pump 20 is connected by a three-way valve either to a "sniffer" pipe which opens in the ship's wheel house or to an exhaust pipe.

Internally the housing 17 of each unit has a matt black non-reflective finish. The housing 17 which is preferably a fabricated steel housing, although it could be a plastics casting, defines an air path connecting the two sockets 19 and 21. The air path comprises a lower horizontal path 27 between walls 17d and 17f leading from the inlet connection 19; an upper mainly horizontal path 28 between walls 17c and 17e leading to the outlet connection 21; and vertical connecting path 29 leading from a square aperture 30 in the wall 17f to upper horizontal path 28. A tubular sighting duct 31 opens into the upper path 28 and is closed off by an angled glass window 32.

The union 16 is, as described above, secured to the top wall 17c of the housing 17 and is located close to the outlet connection 21. A second rod 33, which is similar to rod 16, has an end aligned with the inner end of the rod 15 in the intermediate wall 17e. Short lengths of tubing 34 are provided on and extending slightly beyond the projecting ends of the rods 16 and 33 so that these ends are not visible through the sighting duct 31. The gap between the ends of the rods 15 and 33 provides a first smoke detector as will be described in detail below.

An air-flow indicator, in the form of three flexible nylon wands 36, which are white or any other bright colour, is located close to the air outlet 21. When air passes along the air path, the nylon wands 36 are deflected from their vertical position and wave in the air flow.

The second rod 33 leads to a second smoke detector 37. This smoke detector 37 comprises a block 38 in which are formed two light passages 39 and 40. The light passages 39 and 40 open in a projection 41 of the block 38 which is located in an aperture in wall 17d. These light passages 39 and 40 are inclined to the wall 17f by a small angle of about 15°. The continuation of the light passages 39 and 40 meet a short distance before the front face of the block leaving a small flat plateau 42 between the light passages 39 and 40. This plateau 42 prevents dust lodging at the intersection of the light passages. The second rod 33 terminates short of the surface 38. At the outer end of the light passage 41, there is provided a cadmium disulphide, photo resistive

light sensitive cell 43. Light from the rod 33 enters the passage 39 remote from plateau 42 and on leaving this passage 39 will normally be absorbed by the matt black upper surface of wall 17d or will be reflected into and absorbed by the vertical connecting path 29. Normally (i.e. when there is no smoke) no light is deflected into the passage 41 so that the light sensitive cell 43 is in total darkness. This cell 43 is connected to a circuit associated therewith, the circuit plate 44 of which is mounted above the block 38. A slot-in connector 45 is mounted on the rear wall 17b of the container to connect the circuit to the main power and alarm circuit. A zone indicator light 46 is mounted on the front wall 17a, and connected to the unit circuit.

The unit circuit Cr of the cell 43 (LC) is shown in FIGURE 5. The cell LC is connected to the variable outlet of a 1 megohm potentiometer P and through an 0.1 megohm resistor Res to the base of one transistor T₁ of a Darlington pair. The common collector is connected to a relay R₁. This relay R₁ controls a relay-switch RS connected in across the supply in series with the zone indicator light 46. The relay switch RS is also connected to the main alarm system through a diode D.

The unit circuit is fed from a common stabilised power supply circuit. Mains power is fed to the primary of an input transformer having a 24 v. and a 40 v. secondary winding SW₁ and SW₂. One winding SW₁ has two lamps 12 connected thereacross. A relay R₂ is connected in parallel with the lamps 12. A pair of relay switches R₂S₁ and R₂S₂ are provided across the lamp pair. These switches normally, i.e. when the relay R₂ is energised, connect the lamps 12 to the winding SW₁. The other winding SW₂ is connected to a rectifier bridge B. A smoothing capacitor C₁ extends across the bridge output. Connected to the negative line is a Zener diode Z connected via a 5K ohm resistor R₃ to the positive line. The junction of the Zener diode Z and resistor R₃ is connected to the base of the transistor T₃ and to a capacitor C₂ leading to the negative line. The transistor collector leads to the positive line and the emitter is connected to the positive line and through a capacitor C₃ to the negative line. In the negative and positive lines are two relay switches R₂S₃ and R₂S₄ respectively. When the relay R₂ is energised these switches connect these lines to the bridge B.

The relay switches R₂S₁, R₂S₂, R₂S₃ and R₂S₄ are two position switches. When the relay is de-energised, as on mains power failure, these switches connect the lamps and the power lines of the supply circuit in parallel to a standby battery unit By.

When light falls on the cell LC (43) as will be described its resistance falls sharply causing the Darlington pair to conduct. This results in the relay switch R₁S₁ being closed lighting the zone lamp 46 and energising the main relay R₁ which causes the main fire alarm to be activated.

A shut-off butterfly valve 49 is provided to seal off the aperture 30 thereby preventing flow through the vertical path 29. A handle 51 is located on the front face 52 of front wall 17a for controlling the position of the valve 49. This valve 49 is provided to isolate a hold containing a substance, such as cement, which will not burn but which gives off dust that will be sucked through the apparatus causing the alarm to be given and the apparatus to be dirtied.

The valve 49 is movable by the handle 51 from a fully open to a fully closed or sealed position. The valve 49 may also be adjusted to lie in the continuation of the light path 39 to reflect light into the light path 41 so as to test the operation of the apparatus.

A conventional fault circuit is connected to the lamp 12 to give a "fault" signal should this lamp fail.

In use, the units connected to holds containing non-burning and dusty substances are shut off by their valves

49, the three-way valve connects the pump outlet to the "sniffer" pipe, the common lamps 12 are illuminated, and the suction pump 20 is operating. The nylon wand air-flow indicator 36 will wave in the air flow so that a viewer can check that air is passing through the air path in each housing. While there is no smoke to be detected, the cells 43 will remain in darkness and the circuits will give no signals.

Should fire or smouldering commence in one of the holds, the smoke given off will be drawn through the air path of the associated detector unit 11. When the smoke particles pass along lower path 27 through the continuation of the light passage 39, these particles will deflect light into passage 41 causing this light to fall on the cell 43. This will have the effect of decreasing the resistance of the cell 43 causing the Darlington pair to conduct energising the relay R₁ with the result that the "alarm" signal will be emitted. The smoke particles when passing through the gap between the rods 16 and 33 will also reflect light which is visible through the sighting duct 31. The officer in the wheel house having been warned by the alarm signal can now make a visual check by looking through the appropriate sighting duct 31.

The electric and the visual indications of smoke will be given by the apparatus at very low smoke concentrations. We have found that the first or visual detector will give an indication of smoke at as low a concentration as two percent obscuration per foot whilst the electric or second detector is even more sensitive. Thus remedial fire fighting action can be taken at a very early stage.

The first or visual detector provided by the gap between the rods 15 and 33 also serves to actuate the second or electric detector at low smoke concentrations as will now be described. The light leaving the inner end of the rod 16 disperses in the shape of a cone. Of this cone of light only the central cylindrical part falls on the end of the rod 33. The remaining part of the cone of light, which part is herein defined as the cone annulus, does not fall on the end of the rod 33. When there is a low concentration of smoke particles in the air drawn into the air path, these particles, when in the cone annulus, will reflect light on to the end of the rod 33. Thus more light will pass from the light passage 39 and the scatter light falling on the cell 43 will likewise increase. This in turn will reduce the resistance of the cell 43, causing the Darlington pair to fire so that the "alarm" signal will be given in the unlikely event it has not already been given.

The invention is not limited to the precise constructional details hereinbefore described and illustrated in the drawings. For example, the block 38 may be recessed at the commencement of the light path. Thus scatter light leaving the end of the rod 33 will be absorbed in the recess to a substantial extent and will not be reflected down the path 39. Instead of the tubing 34, low ridges 55 may be provided to mask the ends of rods 15 and 33. A flashing zenon light, flashing every five seconds, may replace the quartz iodine lamp. The apparatus can also be used in a building where a number of rooms or zones are being policed by the fire detection apparatus.

60 We claim:

1. Smoke detection apparatus in which a stream of air, possibly carrying smoke particles, is passed through a dark chamber, provided with a viewing window, a light source being provided to illuminate any smoke particles in said stream of air to render the same visible and a light sensitive cell, screened from said light source, being arranged in said chamber to be illuminated by reflected light from smoke particles in said stream of air characterised in that the stream of air is moved past one end of a light-carrying rod (15, 33) and through a gap in said rod to provide two separate positions at which smoke particles in said air stream are illuminated from a common light source.

2. Smoke detection apparatus according to claim 1,

further characterised in that the air stream passes along a pair of substantially parallel paths (27, 28) through said dark chamber, the gap in said light-carrying rod (15, 33) lying in one path (28) and the end of said rod lying adjacent the second path (27), the portion (33) of said light-carrying rod being bent between said paths so as to direct light obliquely into said second path (27), the light sensitive cell (43) being adjacent to the end of light-carrying rod portion (33), but shielded from the beam of light emitted therefrom.
